CLAIM

The ornamental design for a carrier, as shown and described.

DESCRIPTION

FIG. 1 is a perspective view of a carrier showing my new design according to an exemplary embodiment and in a first arrangement.

FIG. 2 is a front elevation view of the carrier of FIG. 1, the rear elevation view is a mirror image.

FIG. 3 is a right elevation view of the carrier of FIG. 1, the left elevation view is a mirror image.

FIG. 4 is a top plan view of the carrier of FIG. 1.

FIG. 5 is a bottom plan view of the carrier of FIG. 1.

FIG. 6 is a perspective view of the carrier of FIG. 1 in a second arrangement.

FIG. 7 is a front elevation view of the carrier of FIG. 6, the rear elevation view is a mirror image.

FIG. 8 is a right elevation view of the carrier of FIG. 6, the left elevation view is a mirror image.

FIG. 9 is a top plan view of the carrier of FIG. 6.

FIG. 10 is a bottom plan view of the carrier of FIG. 6; and, FIG. 11 is a plan view of the carrier of FIG. 1 shown in an unfolded arrangement.

The broken lines showing cans illustrate environmental structure. All other broken lines represent portions of the carrier. The broken lines form no part of the claimed design.
